CLAIM

The ornamental design for a combined dental floss and brush device, as shown and described.

DESCRIPTION

FIG. 1 is a perspective view of a combined dental floss and brush device, showing my new design;

FIG. 2 is a front view of the combined dental floss and brush device;

FIG. 3 is a back view of the combined dental floss and brush device;

FIG. 4 is a left-side view of the combined dental floss and brush device;

FIG. 5 is a right-side view of the combined dental floss and brush device;

FIG. 6 is a bottom view of the combined dental floss and brush device; and,

FIG. 7 is a top view of the combined dental floss and brush device.

In the drawings, the broken lines illustrate portions of the combined dental floss and brush device, and form no part of the claimed design.

1 Claim, 5 Drawing Sheets
